UNITED STATES PATENT OFFICE

CHARLES J. NAGLE, OF HERKIMER, NEW YORK

LIQUID AGITATION COOLER

Application filed June 10, 1929. Serial No. 369,910.

This invention relates to agitators and more particularly to mechanical agitating means for water to be used in connection with any submerged type milk cooler of any conventional type of manufacture.

The primary object of this invention is, therefore, the provision of mechanical means, either in the nature of a propeller of any design, operated by any mechanical means and having full revolution such as a pump, propeller fan, worm or by any design of paddle which has part revolution, in any way mechanically operated in order to set up an agitation or circulation of water currents in any type of submerged cooler.

A still further object of the invention is to control said agitation or current by the mechanical means above mentioned, by the provision of one or more mechanical agitating means placed at various points in association with the cooler as may be desired by the design or shape or location of the refrigerating unit, whether it be mechanical, or as illustrated in the annexed drawing, in the form 25 of a metal container for ice or like cooling medium.

A still further object of the invention is to provide, in connection with the agitating means, a mechanical refrigerating unit, 30 which is preferably in the form of a metal container, especially shaped and designed to control the agitation or water current as before mentioned.

The above and numerous other objects will 35 become apparent during a study of the following description taken in connection with the accompanying drawings, wherein:

Figure 1 is a top plan view of a cooler of conventional construction, with my improved cooling means and agitation device associated therewith, the cooler being shown with the cover thereof removed.

Figure 2 is a longitudinal section therethrough.

Figure 3 is a vertical transverse section through the cooler and fully illustrating the design of the cooling medium container.

Figure 4 is a perspective of the cooling medium container.

With reference more in detail to the draw-

ing it will be seen that the reference character 5 denotes a cabinet constructed in accordance with the conventional form of cooler cabinet.

The cooler as herein shown is preferably 55 of rectangular configuration and of suitable depth so as to receive milk cans or containers 6 as illustrated. The container 5 is preferably opened at its top and has a bar 7 extending transversely across the opening, said bar 60 7 being fixed at its opposite end to the side wall of the cooler cabinet, in any suitable manner.

Suitable closures or doors 8 are hinged to one side wall of the cooler cabinet as at 9 and 65 it will be noted that when the doors are in closed position, the same are supported by the cross member 7 and adjacent portions of the sides and the end walls of the cooler cabinet. It may be well to mention that the cabinet is also suitably lined as at 11, to provide 70 a water tight container.

As illustrated in Figure 4, the ice container is preferably formed as an elongated trough-like casing of substantially T-shaped formation and comprising the side walls 10, end walls 12 and a bottom wall 13. The container is preferably T-shaped in formation so as to provide the elongated upper ice receiving portion 14 and the relatively shorter lower 75 compartment 15. At their upper edge, the side walls 15 of the container are flanged as at 16, the flange extending for the full length 80 of the container and being provided with a plurality of bolt receiving openings 17. In practice, the ice receiving container is secured to the under face of the cross bar 7, to 85 depend transversely of the cooler cabinet, the bottom of the ice container terminating in spaced relation and above the bottom of the 90 cooler. Of course, it is to be understood that the ice container is held suspended from the cross member 7 through the medium of bolts or other suitable fastening means fastened 95 through the openings formed in the flanges 16 and through the said cross member 7 in an obvious manner. One end wall of the ice container is preferably provided with an opening 18 to receive piping for the refrigerant units located within the container.

The adjacent side wall of the cooler is provided, of course, with a suitable opening 19, in registry w' h the opening 18 to facilitate the coupling of the pipe connection when a mechanical refrigerant is disposed within the 5 said container.

In practice, the cooler chest is filled with water and the milk cans 6 are submerged therein. The water of course is cooled by 10 the refrigerant within the container, especially adapted for that purpose. In order to agitate the water within the cooler, I provide suitable agitating means herein designated generally by the reference character 15 A. The said agitating means A is supported on a shelf or platform 18 located exteriorly of the casing and supported by brackets 19 fixed in a suitable manner to one wall of the cooler 5 adjacent the bottom of the cooler. A 20 suitable electric motor 22 is supported on the platform and the armature shaft 23 of the motor extends through the adjacent end wall of the cooler 5, and to the outer end of said armature shaft is fixed a suitable propeller 24.

From the foregoing then, it will be seen 25 that when the cooler is filled with water, the revolving of the propeller 24 will cause an agitation of the water and the water current caused by said agitation will be controlled due 30 to the particular shape of the refrigerant container as is obvious.

The water being caused to flow beneath the container and through the spaces 25 and 26 caused by the depending bottom portion 15 of the refrigerant container, the end walls of 35 which due to the specific shape of the container are spaced inwardly from the adjacent side walls of the cooler 5 as illustrated.

From the foregoing then, it will be seen 40 that I have provided a simple and novel means for causing the agitation of the cooled water within the cooler whereby milk with which the container is filled will be kept at the desired temperature.

Even though I have herein shown and de- 45 scribed the preferred embodiment of the in- vention and have set forth in detail certain structural elements, it is to be understood that the invention is susceptible to certain changes 50 fully comprehended by the spirit of the in- vention as herein described and the scope of the appended claims.

What is claimed is:

1. In a cooler of the class described, a cabi- 55 net of substantially rectangular configuration open at one end, hingedly mounted doors for closing the opening, an elongated trough located within the cabinet, means for supporting the trough transversely of the cabinet, said trough being of substantially T-shaped for- 60 mation and having its lower end in spaced relation with the bottom of the cabinet, an electric motor disposed exteriorly of the cabi- 65 net, a propeller located within the cabinet, and means operatively associating the pro- 70 peller with the electric motor.

2. In a cooler of the character described, 75 a cabinet open at its top, a plurality of doors hingedly mounted on the top for closing the opening, a cross member transversely of the cabinet at the open top of the cabinet, a sub- 80 stantially T-shaped trough depending from the cross member, a refrigerant medium located within the trough, and said trough hav- 85 ing its lower end portion disposed in spaced relation with the bottom and adjacent side walls of the cabinet, and said cabinet adapted to contain a cooling fluid, a propeller located within the cabinet and submerged in the fluid, an electric motor disposed exteriorly of the cabinet, and means operatively associating the propeller with the electric motor for agitating the cooling fluid within the cabinet.

3. In a cooler of the class described, a sub- 90 stantially elongated rectangular cabinet open at its top, a cross member extending between the side walls of the cabinet at the top there- 95 of, an open top refrigerant container secured at its top to said cross member and depending downwardly therefrom within said cabinet, said container having a relatively elongated upper compartment extending transversely of the cabinet for the full width of the cabinet, and a relatively shorter lower compartment communicating with and depending from said upper compartment, said lower compart- 100 ment of said container having the bottom thereof in spaced relation to the bottom of said cabinet, and a motor-driven rotatable agitating member arranged within said cabi- 105 net at one end of said cabinet.

In testimony whereof I affix my signature.

CHARLES J. NAGLE.
